JOHN T. ROBINSON AND GEORGE E. GOODING, OF BOSTON, MASSACHUSETTS, ASSIGNEES
TO JOHN T. ROBINSON COMPANY, OF BOSTON, MASSACHUSETTS, A CORPORATION
OF MASSACHUSETTS.

BOX-COVERING MACHINE.

Application filed March 24, 1925. Serial No. 17,897.

This invention relates to machines for covering boxes with paper or similar material and has for an object to provide improved tension means for applying a proper tension 5 to the covering material after it is drawn from the source of supply and before the adhesive is applied thereto.

Another object of the invention is to provide means in the adhesive applying mechanism for preventing the covering material 10 from entering the tank containing the adhesive to prevent the adhesive from being improperly applied to the covering material.

A further object of the invention is to provide a vertically adjustable guide roll extension 15 over which the web of covering material passes and by which its length may be increased or decreased to give the proper set to the adhesive before the covering material 20 is applied to the box form. Convenient means are provided whereby the vertical extension can be adjusted by the operator from the forward part of the machine.

The foregoing and other objects of the invention, together with means whereby the same may be carried into effect, will best be understood from the following description of one form or embodiment thereof illustrated in the accompanying drawings.

In said drawings:

Fig. 1 is a side elevation of a machine embodying the invention.

Fig. 2 is a fragmentary plan view of the tension means for the covering material.

Fig. 3 is a side elevation of a part of the mechanism shown in Fig. 2 showing one of the adjustable tension devices in operating position.

Fig. 4 is a side elevation of the adhesive tank having one side thereof cut away to show the improved guard plates which prevent the strips of covering material from entering the adhesive tank.

Fig. 5 is a plan view of the adhesive mechanism shown in Fig. 4.

Fig. 6 is an elevation of the vertically adjustable guide roll extension.

Referring to Fig. 1, the machine as a whole comprises a frame consisting of a front standard 10, a rear standard 11, and a bed portion

12 supported on the front and rear standards. Mounted upon the bed 12 at the front and rear ends and at each side are pedestals 13 at the top of which are supported two longitudinal bars 14. These bars project at the rear and have adjustably secured to the projecting portions a pair of depending arms 15, 15 which carry at their lower ends a transverse shaft 16 adapted to support one or more rolls 17 of paper or similar covering material.

Supported intermediate the bars 14 forwardly of the rolls 17 is a receptacle 18 for glue or other suitable adhesive. This receptacle has journalled in the top so as to extend down into the adhesive contained in the tank, a distributing roller 19 over which the paper or other webs 20 from the rolls 17 pass. Suitable means, not shown, is provided for preventing the roller 19 from turning in a direction at the top towards the rear of the machine, the forward rotation of the roll being obtained by the movement of the strip 20 which passes thereover.

Forward of the roller 19 is supported a scraping device generally indicated at 21 adapted to remove the excess adhesive from the underside of the webs 20, this device being adjustable vertically of either or both ends of the scraper by the operator at the front of the machine by moving the shafts 22 angularly the desired extent to raise the scraper at opposite ends equal or unequal amounts to cause the plate to properly bear against the paper webs and thereby remove the excess adhesive from the underside thereof.

On the forward end of the bed plate 12 is secured an upright bracket 25 which supports the blade mechanism by which the web 20 is severed. This mechanism comprises a fixed blade 26 suitably secured at the front upper edge of the bracket 25 and the bracket also includes journals for a transverse manually oscillatable shaft 27 upon which are mounted arms 28, 28 carrying a movable blade 29 which cooperates with the said fixed blade 26.

The box form 30 is mounted on a horizontally and vertically adjustable supporting mechanism generally indicated at 31 and is power driven by connections from an electric motor not shown. The covering material

- may consist of a plurality of strips 20 led from separate rolls 17 mounted on the shaft 16 at the rear of the machine, said material being drawn to the forward part of the machine over and beneath a plurality of guiding rollers 32 to 43. As shown in Figs. 1 and 2, the strips 20 as they are drawn from the rolls 17 pass under the guide roller 32 up and over the roller 33 and beneath the roller 34 to the upper part of the adhesive applying roller 19. 10 When the machine is operating at high speed and the strips of covering material are drawn quickly through the machine by the rotation of the box form 30, the strips 20 will pile up due to the uneven speed resulting from the 15 irregular form of the box form, to the stopping of the machine and other causes, the result being that the practical operation of the machine is greatly impaired. To assist in overcoming this difficulty, we provide improved tension devices which consist of independently, transversely adjustable holders in the form of collars 44 mounted on a transverse shaft 45, see Fig. 2, the shaft 45 being 20 supported on the rods 14 at the rear of the adhesive tank 18 and at a point adjacent the upper edge thereof. Each of the collars 44 has an adjustable thumb-screw 46 which is threaded in the collar and engages the transverse supporting rod 45. The collars 44 are each provided with a flexible spring member 47 which is secured to the periphery of the collar and extends forwardly over the guide roller 33. As many of these tension devices 25 are provided as there are strips of material applied to the box form. In the present instance there are three tension devices, one for each of the three strips of covering material shown. The spring members 47 are made of relatively light spring metal which permits 30 them to be brought to bear on the covering strips with a varying pressure as the strips pass over the guide roller 33. In operation, it is found, due either to the difference in the materials from which the several strips may 35 be made or to the irregularities in the construction and operation of the machine, that a different tension may be necessary on the different strips of material. Accordingly the 40 machine provides for this difference in tension through the medium of the independent tension devices each of which may be adjusted to apply the required amount of tension to the separate strips of material. 45 As the strips of paper leave the roller 33 they pass under the roller 34 and up and over the adhesive applying roller 19, thence over the guide roller 35 and beneath the guide rollers 36 and 37, the excess adhesive being 50 scraped by the scraper 21 from the under side of the strips 20 at a point between the guide rollers 36 and 37. 55 To prevent the strips 20 from dropping into the adhesive in the tank 18, when in the 60 operation of the machine the said strips be-

come slackened and are permitted to fall, we provide a plurality of guard plates 48, 49 and 50 shown enlarged in Fig. 4, which are supported on opposite sides of the adhesive tank 18 and adjacent the upper edge thereof. The plate 48 is located to the rear of the adhesive roller 19 and beneath the guide roller 34 and substantially closes the opening in the tank between the rear wall and the periphery of the adhesive roller 19. 70

The plates 49 and 50 are located beneath the guide rollers 35, 36 and 37 substantially closing the remainder of the opening in the adhesive tank with the exception of the gap provided for the return of the adhesive scraped from the covering material by the scraping mechanism 21. It will thus be seen that the strips of covering material 20 are prevented at all points in their passage through the adhesive applying mechanism from dropping into the adhesive and becoming improperly coated therewith. The plates 48, 49 and 50 are removably supported on pins 51 in the tank 18 to permit the same to be readily removed to give access to the interior of the tank, and these pins are positioned to support the plates in inclined relation to permit the excess adhesive material dropping on the plates to flow back into the reservoir 18. 80

After the paper strips 20 pass from the adhesive applying and scraping mechanism sufficient time must elapse to give the adhesive the required amount of set before it is applied to the box form 30. To accomplish this the guide roller 39 is mounted on vertically adjustable mechanism, shown enlarged in Fig. 6, which will now be described. 90

Two vertical supporting rods 52 extend upwardly from the rods 14 and are provided at their upper ends with a cross member 53. The roller 39 is mounted on a slid able carriage 54 provided with lugs 55 which are guided on the rods 52. A similar but smaller guiding roller 56 is mounted on the carriage 54 above the roller 39 the strips 20 of covering material passing between the said rollers. 100

The head 54 is raised and lowered on the vertical rods 52 by means of a flexible cable 57 attached to the head 54 and passing upwardly through the cross member 53, over pulleys 58 and 59, and thence downwardly to a winch 60 to which the end of the cable 57 is fastened and which is adapted to wind the cable thereon. 110

The winch 60 is mounted on a longitudinal shaft 61 which extends forwardly along the bed 12 to a point at the forward end of the machine. The forward end of the shaft 61 has a bevel gear 62 secured thereon which cooperates with a similar gear 63 mounted on a shaft 64, the latter being operated by a crank 65, the crank 65 being located in the convenient reach of the operator. Accordingly, when it is found that the set which is being given to the adhesive applied to the 120

115

125

130

135

strips 20 should be greater or less in amount, the crank 65 is turned to raise or lower the guide rollers 39 and 56 and thereby increase or diminish the length of the strips 20 from 5 the adhesive applying mechanism to the point of application to the box form 30. The guide rollers 38 and 40 operate to guide the strip when the rollers 39 and 56 are lowered to a point below the rollers 38 and 40. The 10 guide rollers 41, 42 and 43 complete the guiding of the strips 20 to the forward part of the machine at which point the said strips are severed by the severing mechanism.

What we claim is:

15 In a box covering machine, the combination with a frame, means at one end of said frame for supporting a roll of covering material, means for guiding a strip of the said material from said roll to the opposite end of 20 said frame, mechanism in the latter part of said frame for severing the strip, means in the path of said strip for applying adhesive to the latter, said guiding means including a vertically adjustable roll and means for 25 adjusting said roll comprising a bracket upon which said roll is mounted, vertical guide members for said bracket, and mechanism connected to said bracket and operable from a point adjacent said severing means for 30 raising and lowering the same.

In testimony whereof we affix our signatures.

JOHN T. ROBINSON.
GEORGE E. GOODING.
